United States Patent Office

Des. 180,031
Patented Apr. 9, 1957

180,031

CHAIR

Morton Pearlstine, Cynwyd, Pa., assignor to The Bunting Company, Inc., Philadelphia, Pa., a corporation of Pennsylvania

Application September 23, 1955, Serial No. 38,068

Term of patent 14 years

(Cl. D15—6)

The dominant features of my design reside in the parts shown in solid lines.

I claim:

The ornamental design for a chair, as shown and described.
